UNITED STATES PATENT OFFICE

NORMAN H. RICKER, OF HOUSTON, TEXAS

FLUID PRESSURE OPERATED SWAB

Application filed May 1, 1930. Serial No. 448,832.

My invention relates to the lifting of liquid from deep wells by means of the pressure of gaseous fluid. It pertains particularly to devices of this character in which a swab is employed.

It is an object of the invention to provide an apparatus whereby the liquid may be raised from the well by a single eduction tube and a well casing outside thereof, thus doing away with the use of a separate pipe to conduct the air to the lower end of the eduction tube.

I desire to employ automatic means to control the operation of the device, and yet to use the space between the casing and the eduction tube for the inlet of the pressure fluid to the lower end of the eduction tube.

In the drawings herewith Fig. 1 is a central vertical section through a device embodying my invention. Fig. 2 is a side elevation, somewhat enlarged, showing the swab engaging structure adjacent the upper end of the eduction tube.

My device is an improvement upon the structure shown in the prior patent application of H. W. Fletcher, Serial No. 326,234 filed December 15, 1928, the improvement consisting of eliminating the use of two tubes within the casing.

The casing is shown at 1. It has a casing head 2 at its upper end. Said casing head has a lateral outlet 3 for liquid from the well, and its upper end is closed by an elongated cap 4. The interior of the casing head has an inwardly extending flange providing a shoulder 5 to support the eduction tube.

The gaseous fluid enters the casing head through a lateral inlet 6 connecting with an upwardly curved pipe 7 leading to an automatic pressure fluid regulator A.

The eduction tube 8 is of smaller diameter than the casing below the inlet 6 to provide an inlet passage 9 for the pressure fluid. Within the casing head, the eduction tube connects with a head 10 upon which is a flange 11 to engage upon the shoulder 5 to support the tube in the casing. Above the flange 11 is a sleeve 12 screwed upon the head 10 and adapted to form a seal within the casing head.

Above the head 10, the eduction tube extends upwardly into the outer cap 4, the upper end of the tube being closed, as shown at 13. The sides of the extension 14 are slotted at 15 to allow an outlet for the pressure fluid and the liquid from the well. A slot 16 is also formed to receive a latching dog 17 suspended upon a leaf spring 18, which holds said dog normally in position to engage the swab 19^a.

Below the dog 17 is a sliding collar 19, the upper end of which is beveled at 20, see Fig. 2, to engage beneath the dog 17 and move it out of swab engaging position. Below the collar 19 is a ring 21 secured to the tube extension 14 by welding or the like and serving as a support for a bell crank lever 22. Said lever is pivoted at 23 to the ring and has an upwardly extending lever arm 24, the end of which is slotted at 25 to receive the pin 26 upon an operating yoke 27. There is a short arm 28 on the lever which engages beneath the collar 19 to move said collar when the well is operated.

The lower end of the tube 8 is connected with inlet coupling 29 which forms a seat for the swab, and has an inlet port 30 below the swab seat 31 for the gaseous pressure fluid and an inlet port 32 for the liquid past the swab to the space above. At the lower end of the coupling is a nipple 33 projecting into the liquid.

The swab 19^a fits within the eduction tube. Its lower end is rounded to fit the seat 31. A valve 34 has a stem slidable in the lower end of the swab, and the said valve is normally retained out of its seat by gravity and by fluid pressure below the seat 35. Below the seat are lateral openings in the swab through which liquid or other fluid may pass into and through the swab.

My pressure fluid may be air, gas, or similar fluid forced under pressure through pipe 36 to the pipe 7 by way of the pressure fluid regulator A. Said regulator includes a housing 37, one end of which is secured to the head 2. A cylinder 38 adjacent the head 2 receives a piston 39 upon which is a rod 40 slidable through the wall of the casing head where it is connected with the yoke 27 for 100

operation of the sleeve 19. A plurality of openings 41 about the rod 40 allows the passage of fluid from the casing head to said cylinder.

- 5 A stem 42 on the piston is slideable through a partition 43 at the head of the cylinder and may engage a valve 44 at one side of a chamber 45. Said valve closes an opening in a wall 46 separating chamber 45 from an adjacent chamber 47 with which the pipe 7 is connected. The valve 44 has a stem connected with a head 48 recessed to receive a spring 49 adjustably mounted in a cap 50 on the outer end of chamber 47.
- 10 15 There is a by-pass 51 from the chamber 45 to the chamber 47 adapted to be regulated by a manually adjustable needle valve 52.

In the operation of the device; beginning with the parts positioned as shown in Fig. 1, 20 the plunger has just reached its seat and is ready for the valve to be closed to start upwardly. The pressure fluid entering below the swab closes the valve, and the plunger with its load of liquid is forced upwardly to the surface. The liquid discharges through the outlets 15 and 3, and the plunger moves past the openings, and the back pressure of the fluid entrapped in the cap 13 forces the plunger valve open. The valve 44 is closed 25 simultaneously with the moving of the dog 17 to swab plunger-engaging position by the advancing of the piston 39; this being accomplished by the fluid pressure at the upper end of the casing head while the swab is moving to the end of its upward stroke. The piston 39 is forced outwardly by the pressure fluid passing through openings 41 to the cylinder 38. This shuts off the full line pressure from the well. The air behind the plunger exhausts through the outlet at the upper end of the eduction tube, and the liquid from the well moves up into the eduction tube above the seat 31.

30 35 The pressure fluid then enters only by way of the by-pass 51 and bubbles up through the liquid. But the head of the liquid rising in the eduction tube above the pressure fluid inlet gradually becomes great enough to resist the entry of gaseous pressure fluid until the fluid pressure is great enough behind the valve 44, combined with the pressure of spring 49, to open valve 44 to allow entry of the full line pressure to the well. Simultaneously the piston 39 is moved to release the swab piston which falls with the valve still open. When the swab reaches its seat, the fluid pressure below it quickly operates to close the valve 34, and the operation is again repeated.

40 45 By the use of my device, the cost of the installation is decreased over the old devices of this character, and the operation is still automatically controlled. The device is capable of accurate adjustment and is not liable to get out of order.

What I claim as new is:

1. A well casing, an eduction tube therein, means to seal the space between the upper ends of said casing and tube, means to introduce gaseous pressure fluid into said casing to the lower end of said eduction tube, a swab plunger in said tube, an outlet member at the upper end of said tube, means on said member to engage and hold said swab, and means operable by fluid pressure to release said swab. 70

2. A well casing, an eduction tube therein, a swab plunger in said tube, means to introduce pressure fluid below said swab, means at the upper end of said tube to engage and hold said swab, and means operable by fluid pressure when liquid has entered said tube to release said swab. 80

3. A well casing, an eduction tube therein, a swab plunger in said tube, means to introduce pressure fluid below said swab, means at the upper end of said tube to engage and hold said swab, and means operable when a predetermined level of liquid has risen in said tube to release said swab. 85

4. A well casing, an eduction tube therein, a swab plunger in said tube, means to introduce pressure fluid below said swab, means at the upper end of said tube to engage and hold said swab, a pressure fluid regulator on said casing, a valve in said regulator controlling the entrance of said fluid to the lower end of said eduction tube, and means operable by the movement of said valve through the pressure in said casing to release 90 said swab. 100

5. In combination, a well casing, an eduction tube in said casing, a swab plunger in said tube, a supporting seat for said plunger adjacent the lower end of said tube, means to introduce fluid pressure below said seat to raise said swab, means to catch and hold said swab at the upper end of said tube, and means operable when the liquid has risen a predetermined height above said seat to release said plunger. 105

6. In combination, a well casing, an eduction tube in said casing, a swab plunger in said tube, a supporting seat for said plunger adjacent the lower end of said tube, means to introduce fluid pressure below said seat to raise said swab, means to catch and hold said swab at the upper end of said tube, and means operable by the pressure of fluid in said casing to release said plunger. 110

7. In combination, a well casing, an eduction tube therein, a swab in said tube, a support for said swab adjacent the lower end of said tube, a pressure line to introduce pressure fluid from said line into said casing to a point below said swab, a fluid pressure regulator in said line, a valve in said regulator controlling the passage of fluid to said casing, a by-pass past said valve from said line, whereby pressure fluid can accumulate in said 115 120 125 130

casing to open said valve, and means operable by the movement of said valve to control the falling of said swab.

8. In combination, a well casing, an education tube therein, a swab in said tube, a support for said swab adjacent the lower end of said tube, a pressure line to introduce pressure fluid from said line into said casing to a point below said swab, a fluid pressure regulator in said line, a valve in said regulator controlling the passage of fluid to said casing, a by-pass past said valve from said line, whereby pressure fluid can accumulate in said casing to open said valve, a swab catcher at the upper end of said tube, and means operable by the movement of said valve to control the falling of said swab.

In testimony whereof, I hereunto affix my signature, this 14th day of April, A. D.

20 1930.

NORMAN H. RICKER.
